FINGERPRINT REGISTER

Clayton E. Wyrick, Miami, Fla., assignor to The Egry Register Company, Dayton, Ohio, a corporation of Ohio

Application July 20, 1942, Serial No. 451,644

13 Claims. (Cl. 154—111)

This invention relates to an autographic record machine, and particularly to a record machine wherein an original copy is retained within the machine. More particularly, the invention relates to an autographic record machine for maintaining a continuous sequential record of fingerprints.

An object of the invention is to provide an autographic record machine wherein duplicate original instruments can be prepared and one of the instruments is retained as a record copy.

It is another object of the invention to provide an autographic record machine upon which duplicate originals of fingerprints can be made and one of the originals retained as a record copy.

It is another object of the invention to provide a machine upon which duplicate original instruments can be prepared and simultaneously dated to assist issuance of one of the instruments on the date appearing upon the record copy retained within the machine.

Another object of the invention is to provide a machine for making duplicate original instruments wherein some record is punched upon both of the instruments simultaneously before one of them can be removed from the machine, thus insuring cancellation of the instruments before issuance.

Another object of the invention is to provide a fingerprint register for issuing duplicate originals having the date of issuance punched upon both of the instruments simultaneously.

Another object of the invention is to provide an improved mechanism for controlling the issuance of instruments from a duplicating machine.

Another object of the invention is to provide an improved mechanism for aligning an instrument with respect to the writing opening provided upon an autographic register.

Another object of the invention is to provide an apparatus for keeping a dated sequential record of the issuance of documents.

It is another object of the invention to provide an apparatus for keeping an original sequential record of the issuance of documents in a manner that each of the documents carries the fingerprints of the person issuing the same.

It is another object of the invention to provide an apparatus for performing the foregoing object wherein an original document is maintained as a record and a second original document is originated from the machine, both of which are to carry the fingerprints of the person issuing the same, and which documents must be simultaneous-

ously cancelled or dated before the document can be issued.

It is another object of the invention to provide an apparatus wherein a sequential record of fingerprints of persons passing the apparatus can be maintained, which record can be dated, and a copy of the record retained can be issued to the person whose record is being kept.

Further objects and advantages will become apparent from the drawings and the following description.

In the drawings:

Figure 1 is a top plan view of an autographic record and fingerprinting machine constructed in accordance with this invention.

Figure 2 is a longitudinal cross-sectional view taken along line 2—2 of Figure 1.

Figure 3 is a side elevational view taken along line 3—3 of Figure 1.

Figure 4 is an enlarged cross-sectional view of one of the date punches shown in Figure 2.

Figure 5 is a perspective elevational view of the mechanism of the machine, showing the same at rest position.

Figure 6 is a perspective elevational view of the operating mechanism of the machine, showing the position of the mechanism when starting to issue an instrument from the machine.

Figure 7 is a perspective elevational view of the mechanism of the machine similar to that of Figure 5, showing the mechanism in position just prior to the time the instrument in the machine is to be aligned with respect to the writing table.

Figure 8 is a perspective elevational view of the mechanism of the machine, showing the mechanism in the position just prior to the time the instrument is drawn taut upon the writing table.

Figure 9 is a side elevational view taken along line 9—9 of Figure 1.

Figure 10 is an enlarged cross-sectional view taken along line 10—10 of Figure 2.

Figure 11 is an enlarged elevational view, partially in cross-section, showing the mechanism for frictionally engaging the feed roll for moving the instrument through the machine.

The apparatus of this invention is particularly adapted for use in maintaining a continuous and sequential record, which may be dated, of the issuance of documents from the apparatus. The documents to be issued from the apparatus of this invention are printed upon a continuous web in a manner that two of the documents appear side by side transversely of the web. The documents are in duplicate form and have suitable space thereon

for receiving a mutilating punch which can be constructed and arranged in a manner to indicate the date of issuance or use of the document. The documents can, therefore, be prepared in duplicate original form so that one of the documents can be issued while the other of the documents is retained within the apparatus to maintain a continuous sequential record of the issuance of the documents.

Each of the documents is adapted to receive the fingerprints of a person issuing the same so that the continuous record of documents retained within the machine can be identified with a particular person, who issued the same, upon a particular day of a particular month.

Such an apparatus has particular merit in inspection departments of manufacturing plants wherein it is desirable that an original inspection ticket should accompany the product inspected and that a record shall be kept of the person who inspected the particular product. Since the fingerprints of the person issuing the document are to be placed upon both of the original copies of the document, as well as a suitable date placed upon the document before its issuance, it can readily be seen that a particular product having a particular inspection tag can be checked as to the person who finally inspected the product by merely comparing the fingerprint record upon the particular day of issuance of the inspection tag upon the product. While the example herein set forth merely shows one way in which the applicant's apparatus can be used to a very definite advantage, it will be readily appreciated that there are many similar situations in which it is desirable to be able to check upon a person issuing one of the documents from the machine, or to whom one of the documents has been issued.

In this invention the apparatus consists of a case 10 having a writing table 11. The writing table 11 is substantially U-shaped and is supported by the vertical legs 12. The legs 12 have ears 13 extending therefrom which are suitably secured to the bottom wall 14 of the case 10 by means of bolts 15, or the like.

An aligning bar 16 has the ends thereof extending through the legs 12 of the writing table 11 for free rotation therein. The aligning bar 16 is disposed adjacent the forward edge 17 of the writing table 11. The aligning bar 16 carries a latch device 18 on one end thereof and a latch device 19 on the opposite end thereof, the function of which will be hereinafter described.

A leaf spring 20 is secured to the wall 10a of the case 10 by means of a bar 21 in any suitable manner and extends throughout the length of the aligning bar 16. The upper end of the leaf spring 20 is formed into the shape of a spiral 22 to present a curved edge to the aligning bar 16 when passing thereover during the operation of the machine. This too will be more fully described. The wall 10a is hinged to the bottom wall 14 by means of a hinge 176, the wall 10a being adapted to engage the wall 14 which provides a stop to prevent outward movement of the wall 10a with respect to the case 10. The leaf spring 20, engaging the bar 16, retains the wall 10a in position as shown in Fig. 3.

The machine is of the type adapted to receive a continuous web of fan-folded forms. The pack of fan folded forms 23 is placed within the case 10. The web 24 is threaded over a rod 25 and thence over the aligning bar 16. The web is then positioned upon the writing table 11 and passes

over a bar 26 adjacent the rear edge 27 of the writing table 11.

A feed roll 28 is carried upon a shaft 29 extending between the walls of the case 10. A suitable handle 30 is provided on one end of the shaft 29 to rotate the roll 28. The paper web 24 passes over the feed roll 28 into engagement with a receiving roll 31 carried upon a shaft 32 which extends between the legs 12 of the writing table 11.

The shafts 29 and 32 are provided with pulleys 33 and 34 respectively which receive a spring belt 35. The spring belt 35 provides a friction drive between the pulley 33 and the pulley 34. The pulley 34 is smaller than the pulley 33 so that an overdrive of the pulley 34 is produced. The spring belt 35 can slip upon the pulley 34 to drive the same in a manner to take up the web fed by the roll 28. The slip type friction drive is desirable since the diameter of the receiving roll 31 gradually increases.

The machine of this invention is constructed and arranged to permit production of two original instruments. The fan-folded forms 23 are printed in a manner that the instrument is duplicated upon opposite sides of a preperforated line 36 which extends longitudinally along the web 24 and in the center thereof. Thus, when a form is in position upon the writing table 11 there are two original instruments presented upon which suitable information can be placed. One of the instruments is adapted to be retained as a record copy within the machine, while the second instrument is adapted to be issued from the machine. The instrument which is retained within the machine is received upon a receiving roll 31, while the instrument which is to be issued from the machine passes under a tear-off blade 38 and is directed upwardly by means of a curved end 39 provided on the end of the writing table 11.

The original instruments produced may in this instance be a pair of inspection tickets, one of which accompanies the product which is inspected and the other of which is maintained within the machine as a permanent sequential record of the issuance of the inspection tickets. It is, of course, desirable to indicate the day upon which the inspection tickets were issued, and to insure that both of the tickets will be dated before they are issued so that there can be no conflict of date between comparable original instruments.

In order to provide a date of issuance upon the issued instrument and the record copy of the instrument a month column 40 is printed upon each of the instruments. A day column 41 is also printed on each of the instruments. The day columns 41 are preferably disposed adjacent the perforation line 36, while the month columns 40 are positioned adjacent the outer edge of the web 24.

The writing table 11 has holes therein placed in columns 42, each of the holes in the columns representing one of the months of the year. A second series of holes is provided in columns 43, each of the holes in each of the columns representing one of the days of the month. The columns of holes 42 and 43 in the writing table 11 and the month and day columns 40 and 41 printed upon the web 24 are adapted to be in adjacent relationship when one of the forms is in proper position upon the writing table 11.

A cover 44 is pivoted to the case 10 by means of the pins 45. The cover 44 is normally retained in closed position as shown in Fig. 3, the edge 177

of the cover 44 engaging the top edge of the wall 10a. A leaf spring latch member 178 is fixed to the wall 10a by suitable means such as rivet 179. The latch member 178 has a finger 180 that enters a slot 181 in the edge 177 of the cover 44 to prevent accidental lifting of the cover 44. A plate 46 is pivotally supported by the cover 44 upon studs or pins 47 extending through the side walls of the cover 44. The plate 46 has a series of holes placed in columns 48 which correspond to the series of holes in the columns 42 in the writing table 11. A second series of holes is provided in columns 49 which correspond to the series of holes in the columns 43 in the writing table 11.

A plate 50 carrying punches 51 is positioned upon the plate 46 and the punches 51 thereon extend through the holes in the columns 48. The punches 51 are disposed upon the plate 50 in a manner that they engage corresponding holes in the adjacent columns 49 so that the position of the punches represents a particular day of a month within each of the columns. Plates 52 carrying punches 53 are disposed upon the plate 46 and the punches 53 extend through the holes in the columns 48. The punches 53 are adapted to be positioned in corresponding holes in the columns 48 thereby representing a particular month.

The punches 51 and 53 are similar in structure (as shown in Figure 4). Since all of the punches are similar only one of them will be described. The punch 53 has a shank 54 extending through the plate 46 in one of the holes in the column 48. The shank 54 is provided with a recess 55 thereby forming a head 56. A leaf spring 57 has a slot 58 therein to receive the recessed portion 55 of the shank 54. The spring 57 thus bears between the head 56 of the shank 54 and the plate 46 to secure the punch 53 in position thereon.

It may thus be seen that when the cover 44 is moved downwardly toward the writing table 11 that the punches 51 and 53 will enter certain of the holes in the columns 42 and 43 in the writing table 11, whereby the web 24 will be perforated with a series of holes. This operation thus locates the holes in the web to indicate the date upon which the instrument was issued.

Suitable guide pins 59 are carried by the plate 46 and are adapted to cooperate with holes 60 provided in the writing table 11 for aligning the punches 51 and 53 with respect to the holes in the writing table.

The punches 51 and 53 thus simultaneously will cancel both of the original instruments when the cover 44 is moved downwardly toward the writing table 11. Suitable mechanism, to be hereinafter described, is associated with the feeding mechanism with the web 24 for preventing operation of the feeding mechanism until the cover 44 is moved inwardly and the cover 44 has been moved downwardly toward the writing table 11 to cancel the original instruments thereon by suitable mutilating marks, which in this instance are the date marks. The arrangement of the apparatus prevents issuance of a document, or forwarding of a false document into the machine until it has been suitably canceled, thereby insuring a check upon each and every document that is issued from the machine.

In order to identify the person who has issued an original document, this apparatus provides means for placing the fingerprints of the person issuing the document upon both of the original documents after cancellation of the documents.

An ink pad 61 is supported upon a plate 62

extending from the case 10. The ink pad 61 may be of any type for moistening the finger tips of a person so that they can impress their fingerprints upon both of the original instruments presented upon the writing table 11. The fingerprinting operation can be carried out at any time after the cover 44 is lifted and before the documents are issued from the machine. The provision of the fingerprint record insures identification of the person issuing the document with the duplicate document at any subsequent time. Since one of the instruments is to be issued and one is to be retained as a permanent record it will be appreciated that the fingerprint record system retained on successive instruments issued from the machine is of considerable value for preventing substitution or defrauding of instruments. Also, the simultaneous punching of both of the instruments with similarly located punches insures that the same date of issuance will appear upon both instruments.

The mechanism for feeding the web 24 from the fan-fold pack 23 has been partially described. However, additional mechanism is provided for controlling the issuance of a single instrument upon each operation of the machine and mechanism is provided for preventing return of the instrument to the machine once it has issued.

The drive shaft 29 carrying the roll 28 also carries a ratchet wheel 63. A pawl 64 is spring pressed against the ratchet wheel 63 by means of a spring 65 to prevent counterclockwise rotation of the ratchet wheel 63 and roll 28. The ratchet wheel 63 carries a pin 66 which engages a lever 67 pivoted at 68 to the leg 12 of the writing table 11. When the pin 66 is in engagement with the end of the lever 67 the roll 28 cannot be rotated in either direction.

The lever 67 engages a second lever 69 pivoted by the pin 70 to the leg 12 of the writing table 11. The lever 69 has a slot 71 therein engaging a pin 72 carried upon a plate 73 slidably mounted adjacent the leg 12 of the writing table 11 by means of the pins 74 and 75. The plate 73 has slots 76 and 77 engaging the pins 74 and 75 respectively to permit the plate to be reciprocated upon the pins. The plate 73 has an end 78 adapted to extend above the writing table 11 and is adapted to be engaged by the cover 44 when the cover is closed upon the writing table 11.

An ear 79 extends upwardly from the plate 73 and is urged into engagement with a recess 80 provided on the latch device 18 by means of a spring 81. A similar recess 81 is provided upon the opposite side of the latch device 18. This recess 81 is engaged by a catch 82 pivoted upon a pin 83. A spring urges the catch 82 into engagement with the recess 81.

The latch device 19 provided on the opposite end of the aligning bar 16 has recesses 85 therein. These recesses are adapted to be engaged by a catch 86 provided on one end of the lever 87 pivoted upon a pin 88 carried by the leg 12 of the writing table 11. The catch 86 is urged against the latch device 19 by means of a spring 89.

A wheel 91 is carried upon the shaft 29 and is adapted to be rotated therewith. The wheel 91 carries a pin 92 which engages the lever 87 during operation of the mechanism in a manner to be hereinafter described.

The paper web 24 is retained in engagement with the feed roll 28 by means of an auxiliary roll 93. The roll 93 is carried upon a shaft 94 having bearing wheels 95 disposed thereon. The

bearing wheels 97 have a recess 98 adapted to be disposed within slots 95 provided in the ears 96 extending downwardly from the plate 62. A spring 99 has one end thereof in engagement with the bearing wheels 97 and the opposite end surrounding a tongue 100 provided in the ears 96. The spring 99 thus urges the auxiliary roll 93 into engagement with the feed roll 28 to frictionally engage the web 24 and thus permit the same to be fed by the feed roll 28.

The feed roll 28 has a recess 101 in the surface thereof which permits the web 24 to move with respect to the feed roll 28 during a certain period of operation of the device to be herein-after described.

In order to issue a document from the machine the wall 10a is first moved inwardly upon the hinge 176. Inward movement of the wall 10a removes the finger 180 from the notch 181 in the cover 44 and simultaneously releases engagement of the edge 177 of the cover 44 with the top edge of the wall 10a whereby the top cover 44 can be pressed downwardly so that the date punches 51 and 53 will pierce the web 24 and cancel a pair of original documents that are resting upon the writing table 11. The cover 44 may then be lifted to expose the canceled document to receive data and fingerprints before issuing the same. When the cover 44 is moved downwardly the mechanism for issuing a document is unlocked to permit its operation after data and fingerprints have been placed on the documents.

The extension 18 on the plate 73 is engaged by the cover 44 causing the plate 73 to move downwardly. Downward movement of the plate 73 removes the ear 79 from engagement with the recess 80 on the latch device 18 and causes engagement of the catch 82 with the recess 81, whereby the latch device 18 is imparted with a partial rotation. This position of the apparatus is shown in Figure 6. It will be noted that the ear 79 engages a high point of the latch device 18 and cannot return to its previous position (as shown in Figure 5).

When the plate 73 moves downwardly the lever 69 rotates about the pin 70 in a counterclockwise rotation to rotate the lever 67 whereby the pin 66 on the ratchet wheel 63 is released.

With the plate 73 in the position shown in Figure 6, as produced by the downward movement of the cover, the handle 30 can be rotated to feed the web through the machine after the data and fingerprints have been placed on the documents. Since the web 24 is frictionally retained between the roller 28 and the auxiliary roller 93 the web will be pulled through the machine and the roll 31 will receive the copy of the instrument to be retained within the machine. The perforation line 36, extending longitudinally of the web 24, provides a separation line between the copy of the instrument to be issued from the machine and the copy of the instrument to be retained in the machine. The copies are separated by the forward advancement of the web through the machine since the issued copy is directed in an upward direction and the retained copy is moved downwardly into the machine.

The forward advancement of the web 24 rotates the aligning blade 16 due to the drag of the paper upon the edge of the blade. The blade 16 will rotate until the catch 86 on the arm 87 engages one of the recesses 85 provided in the latch device 19.

Further rotation of the handle 30 will feed the web through the machine but the web will slide

over the aligning bar 16. This position of the machine is shown in Figure 7.

Advancement of the web is continued until one of the fold lines 102 between adjacent forms 5 approaches the leading edge 103 of the parallelogram shaped aligning bar 16. The fold line 102 will engage the edge 103 of the aligning bar 16 and, just prior to the engagement thereof, the pin 92 on the wheel 91 will engage the arm 87 to release the catch 86 from the recesses 85 in the latch device 19, whereby the aligning bar 16 is free to be rotated by the web 24.

Continued forward advancement of the web 24 will then rotate the aligning bar 16 and the 15 latch devices 18 and 19 until the ear 79 on the plate 73 engages the recess 81 on the latch device 18, whereby the rotation of the aligning bar 16 is halted. This position of the machine is shown in Figure 8. At this time the lever 67 will be returned by the spring 104 to its initial position so that the pin 66 on the ratchet wheel 63 will engage the same.

As noted in Figure 8, the pin 66 is not yet in engagement with the lever 67. The slight movement provided at this point is sufficient to draw the web 24 taut upon the writing table 11. When the aligning bar 16 has stopped rotation the recess 101 in the feed roller 28 will be adjacent the auxiliary roller 93 so that momentarily the web 24 is released from the feed roll 28. The feed roll can then be rotated independently of the web 24 until the rear edge of the recess 101 again causes engagement of the web 24 with the auxiliary roll 93. After the engagement of the roll 35 in this manner the web 24 will be pulled taut upon the writing table. The machine is then in position as shown in Figure 5, a new document having been brought upon the writing table 11. The cover 44 can then be closed and will be locked in closed position by the latch 178 until the wall 10a is again moved inwardly to institute another cycle of operation.

It will be recognized that the machine herein described provides a record machine wherein duplicate original instruments in writing can be made, one of which is to be issued and the other of which will be retained as a record copy. The machine also provides for simultaneous dating of the instruments and for placing the fingerprints of a person upon both copies, or both instruments.

While the apparatus disclosed and described herein is a preferred form of the invention, yet it is to be understood that mechanical modifications can be made without departing from the spirit of the invention, and that all such modifications as fall within the scope of the appended claims are intended to be included herein.

Having thus fully described my invention what I claim as new and desire to secure by Letters Patent is:

1. In a duplicating machine for handling a fan-folded web, a writing table, an aligning bar rotatably disposed adjacent the leading edge of 65 said writing table and having fold engaging edges 70 said writing table and having fold engaging edges thereon adapted to be engaged by a fold in the web passing over said writing table to rotate said aligning bar, latch means carried by said bar, means for releasing said latch means to permit rotation of said bar when a web is being drawn thereover, and means for holding a fold engaging edge of said bar in alignment with said writing table when a fold in the web engages an edge of said bar, whereby the web is positioned 75 upon said table.

2. In a duplicating machine for handling a fan-folded web, a writing table, a feed roller disposed below said writing table, an auxiliary roller, means for urging said auxiliary roller into engagement with said feed roller, an aligning bar rotatably disposed adjacent the leading edge of said writing table and having fold engaging edges adapted to be engaged by a fold in the web drawn across the writing table, latch means carried by said bar, means for preventing rotation of said feed roller, means interconnecting said last mentioned means and said latch means to disengage said last mentioned means when said latch means is disengaged, and means for halting rotation of said aligning bar when a fold engaging edge thereof is aligned with said writing table and engaged by a fold of the web drawn across said table.

3. In a duplicating machine for handling a fan-folded web, a writing table, a feed roller disposed below said writing table, means holding said roller from rotation, an auxiliary roller, means for urging said auxiliary roller into engagement with said feed roller, an aligning bar rotatably disposed adjacent the leading edge of said writing table and having edges adapted to be engaged by a fold in the web drawn across the writing table, latch means carried by said bar, means for disengaging said latch means, and means actuated by said disengaging means for releasing said feed roller holding means to permit rotation of said feed roller.

4. In a duplicating machine for handling a fan-folded web, a writing table, a feed roller, an auxiliary roller in pressure engagement with said feed roller, means for preventing feed rotation of said feed roller, an aligning bar rotatably disposed adjacent the forward edge of said writing table, latch means carried by said aligning bar, catch means for preventing rotation of said latch means, said catch means having means for causing rotation of said latch means when said catch means is released from said latch means, and means interconnecting said catch means and said means preventing feed rotation of said feed roller for releasing said feed roller holding means to permit feed rotation thereof.

5. In a duplicating machine for handling a fan-folded web, a writing table, a feed roller, an auxiliary roller in pressure engagement with said feed roller, means for preventing feed rotation of said feed roller, an aligning bar rotatably disposed adjacent the forward edge of said writing table, latch means carried by said aligning bar, catch means for preventing rotation of said latch means, said catch means having means for causing rotation of said latch means when said catch means is released from said latch means, a second latch means carried by said aligning bar, catch means for engaging said second latch means upon partial rotation of said aligning bar, means interconnecting said first mentioned catch means and said means preventing feed rotation of said feed roller for releasing said feed roller holding means to permit feed rotation thereof, and means actuated by rotation of said feed roller for releasing said second latch means when a fold in the web engages the aligning bar.

6. In a duplicating machine for handling a fan-folded web, a writing table, a feed roller, an auxiliary roller in pressure engagement with said feed roller, an aligning bar rotatably disposed adjacent the forward edge of said writing table and having a fold engaging edge, latch means carried by said aligning bar, catch means for preventing

rotation of said latch means, said catch means having means for causing rotation of said latch means when said catch means is released from said latch means, a second latch means carried by said aligning bar, a second catch means for engaging said second latch means upon partial rotation of said aligning bar, means preventing feed rotation of said feed roller, means for releasing said feed roller holding means to permit feed rotation thereof, and means actuated by rotation of said feed roller for releasing said second latch means when a fold in the web engages the fold engaging edge of the aligning bar, said first catch means engaging the fold engaging edge of the first latch means when said aligning bar is aligned with said writing table.

7. In a duplicating machine for handling a fan-folded web, a writing table, a feed roller, an auxiliary roller in pressure engagement with said feed roller, an aligning bar rotatably disposed adjacent the forward edge of said writing table having a fold engaging edge, latch means carried by said aligning bar, catch means for preventing rotation of said latch means, said catch means having means for causing rotation of said latch means when said catch means is released from said latch means, a second latch means carried by said aligning bar, a second catch means for engaging said second latch means upon partial rotation of said aligning bar, means preventing feed rotation of said feed roller, means for releasing said feed roller holding means to permit feed rotation thereof, means actuated by rotation of said feed roller for releasing said second latch means when a fold in the web engages the fold engaging edge of the aligning bar, said first catch means engaging said first latch means when the fold engaging edge of the aligning bar is aligned with said writing table, and a cover for the duplicating machine for engaging said first catch means to release said first mentioned latch means.

8. In a duplicating machine for handling a fan-folded web, a writing table, a feed roller, an auxiliary roller in pressure engagement with said feed roller, means for preventing feed rotation of said feed roller, an aligning bar rotatably disposed adjacent the forward edge of said writing table having a fold engaging edge, latch means carried by said aligning bar, catch means for preventing rotation of said latch means, said catch means having means for causing rotation of said latch means when said catch means is released from said latch means, a second latch means carried by said aligning bar, a second catch means for engaging said second latch means upon partial rotation of said aligning bar, means for releasing said feed roller holding means to permit feed rotation thereof, means actuated by rotation of said feed roller for releasing said second latch means when a fold in the web engages the fold engaging edge of the aligning bar, said first catch means engaging said first latch means when the fold engaging edge of the aligning bar is aligned with said writing table, a roll for receiving a record copy for retention in the machine, and a spring belt drive means between said feed roller and said receiving roll.

9. An apparatus upon which duplicate original instruments laying side by side in the same plane can be prepared and be simultaneously impressed with an identifying mark comprising a writing table upon which the instruments are positioned side by side to receive written inscriptions thereupon, a cover for said writing table movable over

said table and the instruments thereon and impervious to prevent alteration of the inscription where the cover is over said table, and means on said cover for producing identifying marks simultaneously upon said duplicate original instruments when said cover is moved thereover, said identifying mark means consisting of duplicate devices on said cover and co-operating duplicate devices in said table which co-operate to simultaneously pierce said duplicate instruments when said cover is moved downwardly upon said table.

10. An apparatus upon which duplicate original instruments laying side by side in the same plane can be prepared and can be simultaneously impressed with a mutilating mark to simultaneously cancel both instruments comprising a writing table having openings therein arranged in columns upon which the instruments are positioned side by side to receive written inscriptions thereupon, a cover for said table movable over said table and the instruments thereon and impervious to prevent alteration of the inscription where the cover is over said table, and punch means carried by said cover, said punch means being adapted to enter the openings in said writing table to simultaneously produce mutilating identifying marks in similar locations upon both instruments placed upon said writing table.

11. An apparatus upon which duplicate original instruments laying side by side in the same plane can be prepared and be simultaneously impressed with identifying marks comprising a writing table upon which the instruments are positioned side by side to receive written inscriptions thereupon, means for drawing a printed web across said writing table, a cover for said writing table to prevent access to said table and the instruments thereon, latch means for holding said cover in position above said table, means to prevent feeding rotation of said drawing means, means engageable by said cover to release said

drawing means, identifying mark means on said writing table, and identifying mark means carried by said cover for cooperating with said mark means on said writing table, said cover being movable downwardly toward said writing table upon release of said latch means to cause cooperation between said identifying mark means to impress the same upon said instruments on said table before said cover is lifted therefrom to expose said instruments and to simultaneously release said drawing means.

12. A record system for issuing an original document and maintaining a sequential original document record of the documents issued which consists of a web having a plurality of original documents arranged in duplicate pairs side by side upon the face thereof, a container for said web, a mechanism for moving the web through the container in increments of a single pair of documents, and means for simultaneously canceling both of the documents before a sequential document can be fed through the container.

13. An apparatus upon which duplicate original instruments can be prepared and be simultaneously impressed with identifying marks comprising a writing table, means for drawing a printed web across said writing table, means to prevent feeding rotation of said drawing means, means to release said drawing means, identifying mark means on said writing table, a cover for said writing table, and identifying mark means carried by said cover for cooperating with said mark means on said writing table, wall means adjacent said writing table for preventing movement of said cover with respect to said table, said wall means being movable with respect to said cover to permit said cover to move downwardly upon said writing table to cause cooperation between said identifying mark means to impress the same upon the printed web on said table and to simultaneously release said drawing means.
